UNDERWATER SPEAR GUN

Jack K. La Trell, Glendale, Calif.

Application June 14, 1948, Serial No. 146,959

Term of patent 14 years

(Cl. D30—1)

To all whom it may concern:

Be it known that I, Jack K. La Trell, a citizen of the United States and a resident of Glendale, California, have invented a new, original, and ornamental Design for an Underwater Spear Gun, of which the following is a specification, reference being had to the accompanying drawing, forming part thereof.

Referring to the drawing:

I claim:

The ornamental design for an underwater spear gun, as shown.

JACK K. LA TRELL.
